WILLIAM C. SHIPHERD, OF WILLOUGHBY, OHIO.

Letters Patent No. 96,152, dated October 26, 1869.

IMPROVEMENT IN SHOE-LASTS.

The Schedule referred to in these Letters Patent and making part of the same

To all whom it may concern:

Be it known that I, WILLIAM C. SHIPHERD, of Willoughby, in the county of Lake, and State of Ohio, have invented a new and useful Improvement in Shoe-Lasts; and I do hereby declare that the following is a full, clear, and exact description thereof, which will enable others skilled in the art to make and use the same, reference being had to the accompanying drawings, forming part of this specification.

The object of this invention is to provide an improved means of attaching and detaching the instep-block of the last with the main part thereof.

The invention consists of a graduated adjustable circular notched catch-plate, attached to the last, and a spring-catch on the instep-block of peculiar construction, arranged for operation in conjunction with the said catch-plate, all as hereinafter more fully specified.

Figure 1 represents a longitudinal sectional elevation of my improved last, and

Figure 2 represents a plan view with the instep-block removed.

Similar letters of reference indicate corresponding parts.

A represents a circular notched catch-plate, pivoted eccentrically in a recess in the face of the seat of the instep-block B, having several notches at various distances from the centre, and clamped down against the bottom of the recess, wherein it is fitted by the pivot-screw, so as to be held firmly in any position to which it may be adjusted. In front of the said clamping-plate is a groove, C, for the point of the catch, and

behind it another groove, D, to make room for the shank of the catch.

E represents the catch, pivoted at F in a recess, G, in the lower face of the instep-block. This catch is provided with a spring, H, connected to the rear end thereof, and bearing at its front end against the bottom of the recess, so as to throw the hook of the catch downward.

The rear end of the catch is provided with a hole, for the connection of a crooked handle or lever, I, for springing the hooked end of the catch up, for disengaging it from the catch-plate, when the block is to be removed.

The lower end of the block is provided with a point, K, in the usual way, for holding it in position, by engaging with the wall of the recess of the last.

The notch of the plate A, with which it is designed that hook shall engage, is adjusted to coincide with the recess C, by loosening the pivot-screw and turning the said plate thereon. By these notches of varying distance, the block B may be held more or less snugly against the wall of the recess at K.

Having thus described my invention, I claim as new, and desire to secure by Letters Patent—

The combination of an instep-plate, B, formed with a hollow recess, G, extending through to the outer end, with the eccentric-notched plate A and spring-catch E, arranged as shown and described.
